[57] CLAIM

The ornamental design for an extension cord clip, as shown and described.

DESCRIPTION

FIG. 1 is a perspective view of an extension cord clip showing my new design;

FIG. 2 is a top plan view thereof, the opposite bottom plan view being a mirror image thereof;

FIG. 3 is a side elevation view thereof, the opposite side being a mirror image thereof;

FIG. 4 is an enlarged end view thereof, the opposite end being identical thereto; and,

FIG. 5 is an enlarged sectional view taken along line 5—5 in FIG. 2.

1 Claim, 3 Drawing Sheets
